(57) **CLAIM**

The ornamental design for a “human body detector,” as shown and described.

DESCRIPTION

FIG. 1 is a right, front perspective view of a “human body detector;”

FIG. 2 is a front view of the “human body detector” of FIG. 1; FIG. 3 is a rear view of the “human body detector” of FIG. 1; FIG. 4 is a right side view of the “human body detector” of FIG. 1;

FIG. 5 is a left side view of the “human body detector” of FIG. 1;

FIG. 6 is a top view of the “human body detector” of FIG. 1; and,

FIG. 7 is a bottom view of the “human body detector” of FIG. 1.

The broken lines are included for the purpose of illustrating portions of the article and form no part of the claimed design.
